Patented Nov. 21, 1972

225,157

POSITIONER FOR POULTRY PRODUCTS AND THE LIKE

Philip L. Reid, Lyman, S.C., assignor to
W. R. Grace & Co., Duncan, S.C.

Filed Dec. 14, 1970, Ser. No. 26,463

Term of patent 14 years

Int. Cl. D15—08

U.S. CL. D11—1

FIG. 1

FIG. 2

FIG. 4

FIG. 3

FIG. 1 is a top plan view of a positioner for poultry products and the like showing my new design;

FIG. 2 is a perspective view thereof on a reduced scale taken from the bottom left edge of FIG. 1;

FIG. 3 is a side elevation thereof as seen from the bottom of FIG. 1 with a poultry product shown in broken lines for illustrative purposes only; and

FIG. 4 is an end elevation thereof as seen from the right of FIG. 1.

I claim:

The ornamental design for positioner for poultry products and the like, substantially as shown and described.
